UNITED STATES PATENT OFFICE.

REUBEN D. WIRT, OF PHILADELPHIA, PENNSYLVANIA.

NOTE-PAPER HOLDER.

1,166,031.

Specification of Letters Patent. Patented Dec. 28, 1915.

Application filed August 12, 1915. Serial No. 45,201.

To all whom it may concern:

Be it known that I, REUBEN D. WIRT, a citizen of the United States, residing at Philadelphia, in the county of Philadelphia and State of Pennsylvania, have invented a new and useful Note-Paper Holder, of which the following is a specification.

The present invention is a device for holding a roll of paper whereby the paper can be drawn or pulled across a portion of the frame or casing to be written upon, and the paper holder is adapted to be hung or secured upon a wall adjacent a telephone, within a kitchen, or elsewhere, for the purpose of writing or recording notes and other memoranda thereon, the portion of the paper written upon being readily withdrawn and detached thereby bringing a clean portion of the paper into position to be written upon.

It is the object of the invention to provide a novel and improved paper holder of the nature indicated, having novel means for accommodating the roll of paper, means for directing the paper from the roll across the casing or frame to be written upon, and means for cutting off that portion of the paper withdrawn from the holder.

The device is of simple, compact and inexpensive construction, is convenient, practical and desirable in use, can be used as an advertising medium or novelty, and is capable of inexpensive manufacture whereby it can be distributed gratuitously by dealers to their patrons or customers for advertising purposes, although the device provides a desirable paper holder for general use and sale.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a front view of the holder. Fig. 2 is a vertical section thereof.

The frame or casing of the holder embodies an elongated or rectangular upright rack 1 constructed of wood or other suitable material to which a hood 2 is attached. The

hood 2 is preferably constructed of sheet metal, and embodies triangular sides 3 having their rear edges secured in any suitable manner to the edges of the back 1, and said hood 2 has an inclined front plate 4 connecting the front edges of the sides 3. The lower end of the hood is open, and the sides 3 of the hood project downwardly below the lower end of the back 1. The upper end of the back 1 projects above the upper end of the hood for attachment to a wall or other support by means of screws or other suitable securing elements. The upper and lower ends of the hood 2 are bent back inwardly, as at 5, for strengthening the ends of the hood and to provide rounded edges for the hood, which is desirable.

Disposed within the lower portion of the hood 2 is a receptacle or carrier 6, which is in the form of a curved or concaved plate disposed transversely between the sides of the hood. The rear wall or flange of the receptacle 6 projects upwardly and overlaps the forward side of the back 1 adjacent the lower end of said back, and said wall or flange of the receptacle 6 has a key-hole shaped opening 7 engageable with a headed screw 8 engaging the back 1 adjacent the lower end thereof. The headed end of the screw projects forwardly from the back to engage through the opening 7 for detachably supporting the receptacle 6. The receptacle 6 is provided between its ends and at its lower portion with a pair of down struck ears 9 providing finger pieces which may be grasped by the thumb and finger of one hand for handling the receptacle 6. When the receptacle 6 is lifted, it can be disengaged from the screw or element 8, and can then be removed for replacing the roll of paper 10. This roll of paper 10 is seated within the receptacle or plate 6 within the hood 2 and may be of any suitable quality. The front wall or flange of the receptacle 6 has its edge bent back or reflexed, as at 11, to provide a rounded edge over which the paper 10 passes. The forward wall or flange of the receptacle 6 projects upwardly above the lower end of the plate 4 and adjacent said plate, and the paper 10 passes over the front wall of the receptacle 6, thence downwardly around the lower end of the plate 4, and thence upwardly over the outer side of the plate 4, as at 12. The outer or exposed portion 12 of the paper rests upon the inclined plate 4, in order that the por-

tion 12 of the paper can be readily written upon when making notes, recording memoranda, etc.

In order to hold the portion 12 of the paper in place upon the plate 4, upper and lower transverse strips 13 are disposed across the plate 4 near the upper and lower ends thereof, and have their ends engaged through slots 14 provided in the plate 4 adjacent the sides 3 of the hood, the ends of the strips 13 being bent back to hold the strips in place. The strips 13 are spaced slightly from the plate 4 to allow the paper to pass upwardly over the plate 4 and under the strips 13. The strips 13 hold the exposed portion of the paper 12 flatly against the plate 4, and prevent the displacement of the paper.

A transverse strip 15 is arranged below the lower end of the plate 4 and has angularly bent ends or ears 16 riveted or otherwise secured to the sides 3 of the hood. The strip 15 serves to strengthen the hood, and also acts as a guard for shielding the lower portion of the hood and receptacle 6 from injury.

The severing device for the paper is carried by the upper end portion of the hood 2, and embodies a transverse cutter blade 17 having angularly projecting ears 18 at its ends overlapping the sides 3 of the hood 2 and pivoted thereto, as at 19, whereby the blade 17 can be swung above and below the upper paper holding strip 13. The upper edge of the blade 17 is bent toward the plate 4, as at 20, while the lower edge of the blade 17 is bent away from said plate, as at 21, to provide a finger piece, while the edge 20 provides a cutting edge engageable with the paper.

A transverse trough 22 has its rear flange riveted or otherwise secured to the back 1 immediately above the hood 2, to provide a pencil holder or receptacle.

The front side of the back 1 above the pencil holder 22 provides a space 23 for bearing suitable advertising matter, enabling the device to be used as an advertising medium or novelty.

In use, the exposed portion 12 of the paper may readily be written upon for any purpose whatever, and the note or memoranda may be withdrawn. This is accomplished by swinging the cutter blade 17 downwardly out of the way, as illustrated in dotted lines in Fig. 2, thus exposing the upper end of the paper which projects above

the upper strip 13. The upper end of the paper may then be grasped and pulled upwardly until the desired length of paper has been pulled above the upper strip 13. The blade 17 is then swung upwardly against the plate 4, and the free portion of the paper may then be torn loose along the cutting edge 20 of the blade 17, this providing a protruding portion of the paper above the upper strip 13 which may be subsequently grasped for pulling out the paper. Instead of cutting the paper loose, each time a note is written thereon, the paper can be withdrawn in a continuous strip containing a series of notes, as will be apparent. When the supply of paper is exhausted, the receptacle 6 can be readily removed to enable a new roll of paper to be placed therein, in which event, the receptacle is replaced within the hood 2 and attached to the back 1, the paper being properly passed over the front edge of the receptacle 6, thence under the lower edge of the plate 4 and thence upwardly over the plate 4 and under the strips 13.

The present device is simple and inexpensive in construction, and can readily be transported by parcel post.

The holder provides desirable means for taking notes or recording memoranda for any purpose whatever.

Having thus described the invention, what is claimed as new is:

A paper holder comprising a casing embodying an upright back and a hood, the hood having triangular sides whose rear edges are attached to the edges of the back and having an inclined plate connecting the front edges of the sides, a concaved receptacle for a roll of paper disposed within the lower portion of the hood and having its back wall detachably engaged to said back, the front wall of the receptacle projecting upwardly above the lower end of said plate and the paper being adapted to be passed over the front wall of the receptacle and under the lower end of said plate, and means carried by the hood for holding the paper upon said plate and to allow the paper to be pulled upwardly thereover.

In testimony that I claim the foregoing as my own, I have hereto affixed my signature in the presence of two witnesses.

REUBEN D. WIRT.
